Primary Examiner—Terry A. Wallace

CLAIM

The ornamental design for a tall screw-top storage container having a base and a lid, as shown and described.

DESCRIPTION

FIG. 1 is a perspective view of the container;

FIG. 2 is front view of the container;

FIG. 3 is a side view of the container;

FIG. 4 is a top view of the container;

FIG. 5 is a bottom view of the container; and,

FIG. 6 is an exploded perspective view of the container.

The rear of the container is identical to, and a mirror image of, the front of the container depicted in FIG. 2. The side of the container opposite to the side depicted in FIG. 3 is identical thereto, and a mirror image thereof.

1 Claim, 6 Drawing Sheets
